UNITED STATES PATENT OFFICE.

HERBERT A. CARHART, OF SYRACUSE, NEW YORK, ASSIGNOR TO REMINGTON TYPE-WRITER COMPANY, OF ILION, NEW YORK, A CORPORATION OF NEW YORK.

TYPE-WRITING MACHINE.

1,256,517.

Specification of Letters Patent. Patented Feb. 19, 1918.

Application filed November 21, 1916. Serial No. 182,555.

To all whom it may concern:

Be it known that I, HERBERT A. CARHART, citizen of the United States, and resident of Syracuse, in the county of Onondaga and 5 State of New York, have invented certain new and useful Improvements in Type-writing Machines, of which the following is a specification.

My invention relates to typewriting machines and has for its principal object to provide certain improvements in the line-lock mechanisms of such machines, and particularly to provide means for locking the space bar of the machine along with the 15 printing keys, so as to insure always a correct margin at the left side of the paper.

To the above and other ends my invention consists in certain features of construction and combinations and arrangements of parts, all of which will be fully set forth herein and particularly pointed out in the 20 claims.

In the accompanying drawings,

Figure 1 is a front-to-rear vertical sectional view on a reduced scale of a typewriting machine having my invention embodied therein, the section being taken partly near the middle of the machine and partly near the right-hand side of the 25 machine.

Fig. 2 is a fragmentary rear elevation, partly in section and showing my novel mechanism.

Fig. 3 is a fragmentary side elevation of 30 the upper rear part of the line-lock mechanism, parts of the machine being shown in section.

Fig. 4 is a perspective view of a portion of the mechanism.

Fig. 5 is a fragmentary plan view of a portion of the mechanism.

In all of the figures parts are broken away or omitted as has been found convenient.

I have shown my invention embodied in 45 a Smith Premier No. 10 typewriter. The main frame of this machine comprises side plates 1, a top plate 2 and a transverse back plate or bar 3 in the base of the machine, said bar connecting the side plates 50 1. Said side plates are connected at the front of the machine by a front plate 4 and a keyboard plate 5. A platen 6 is mounted in a carriage 7 which by means of anti-

friction balls 8 is adapted to traverse a 55 stationary rail 10 which is secured to standards 11 rising from the top plate 2. Said carriage is fed in letter space direction by means of a spring 12 mounted in a drum 13, which drum is rigid on a shaft or axle 14, 60 which is journaled in the back plate 15 and front plate 16 of a framework or housing secured to the under side of the top plate 2. The spring 12 is connected at its inner end with the hub of a large gear 65 wheel 17 journaled on the shaft 14 and meshing with a feed rack 18 on the carriage 7. Another large gear wheel 20, loosely mounted on said shaft 14, meshes with said rack 18 and also with a pinion 70 21, which pinion is loose on the shaft of an escapement wheel 22, which shaft is journaled on pivot screws 23, one mounted in the plate 15 and the other in a bracket 24 secured to the front face of the plate 16. 75 The pinion 21 is connected with the shaft of the escapement wheel by means of a ratchet-toothed clutch 25. The escapement wheel 22 is controlled by feed dogs 26 on a dog rocker 27 which is pivoted on pivot 80 pins 28 passing through the two arms of a bifurcated bracket 30 which is secured by screws 31 to the plate 16.

The type bars 32 are pivoted by means of ball bearings on two segments 33 and 85 are operated by means of radial links 34 and sub-levers 35, the latter pivoted at 36 in a sub-lever segment 37, and each controlled by a returning spring 38. The printing keys 40 have stems 41 passing through the plate 5 and pivoted to bell cranks 42 which are connected by links 43 with the sub-levers 35. Each of said sub-levers has an arm 44 adapted when that sub-lever is operated to move toward the rear of the machine a segmental universal bar 45, which bar is mounted for parallel motion on two transverse rock shafts 46 and 47, the first above the second. The shaft 46 has two up-standing arms 48 which are pivoted to 90 brackets 50 of the universal bar 45 near the ends of said universal bar, and the rock shaft 47 has an upstanding arm 51 from which a pin 52 projects into a slotted ear 53 secured to the universal bar 45 at or 95 near the middle thereof. Said rock shafts 46 and 47 are constrained to rock in unison by means of a link 54 (on the left side of

the machine) connected at its upper end with an arm 55 projecting toward the rear from the shaft 46 and at its lower end with a similar arm 56 projecting rearwardly from 5 the rock shaft 47. The rock shaft 47 is connected with the dog rocker 27 by means of a link 57 pivoted at its upper end to the rearwardly directed arm of said dog rocker and at its lower end to an arm 58 10 projecting rearward from the rock shaft 47, the lower pivot consisting of a pin and slot connection 59 whereby the link is operated by the arm 58, but can move downward independently of said arm when the 15 dog rocker is operated by the space key. A spring 60, acting on the arm 56, constitutes the returning spring for the universal bar. The dog rocker is provided with a returning spring 61 connected at its upper end 20 with a pin 62 projecting from the bracket piece 30 and at its lower end to a long screw 63 screwed into the dog rocker and projecting downward therefrom.

The space key 64 is of the usual Smith 25 Premier construction and arrangement and it has a stem 64^a which is pivoted to a guide link 69 and which is connected with an arm 65 projecting from a fore and aft rock shaft 66 journaled at its ends in the plates 30 3 and 4. Near the back of the machine this shaft has an arm 67 which is connected by a link 68 with a rocking frame or yoke-piece 70 which is pivoted on one of the pins 28 on which the dog rocker is pivoted. This 35 yoke-piece is of peculiar construction, being stamped and bent up out of sheet metal. It comprises a horizontal yoke-part to which the reference numeral 70 is directly applied in Fig. 2 and which lies beneath one of the 40 branches of the bracket 30. The metal is bent upward at the right and left-hand sides of said branch, forming two wings which are perforated and through which perforations the pin 28 passes. From said 45 pin or pivot 28 said wings are prolonged a suitable distance toward the rear of the machine and one of them is bent toward the right or toward the observer's left in Fig. 2 to constitute an arm 71 to a forwardly bent 50 ear of which the link 68 is pivoted. The other wing of the yoke 70 is bent toward the observer's right in Fig. 2, forming an arm 72, the end of which lies over the rearwardly projecting arm of the dog rocker 55. It will be noted that the link 68 is connected with the arm 71 at the rear of the pivot 28 so that when the space key is operated and this link is pulled downward the 60 rear part of the yoke-frame 70 is rocked downward about the pin 28 as a pivot, and the arm 72 causes the dog rocker to rock with the yoke-piece 70, with the result that the space key is operatively connected with the dog rocker independently of the universal bar 45. It will be perceived that the

function of the yoke-piece 70 is to convey the downward motion of the arm 67 and link 68 across the machine toward the observer's right in Figs. 2 and 4, to a point where it is communicated to the dog rocker. 70

The line lock mechanism comprises a transverse bar 73 mounted on arms 74 that hang down from the carriage 7 behind the machine. Said bar 73 is toothed along its upper edge, as shown in Fig. 2, and a line-lock device or slide 75 is mounted on said bar and is adjustable along said bar, said device being retained in adjusted position by means of a spring pressed latch 76 pivoted at 77 to the device 75 and engaging 80 said teeth. On the front face of said line-lock piece or slide 75 there is mounted a bell ringing cam 78 and also a cam 80 made in the form of a roller, said cam or roller constituting a part of the link lock mechanism. 85

The parts of the line lock mechanism on the stationary frame comprise a cross bar 81 pivoted at its ends to the standards 11 in such a way as to be capable of rocking about a transverse horizontal axis. Near its middle said bar has mounted thereon a sliding bolt 82 having a nose 83 adapted to be engaged by the bell ringing cam 78 and by the line locking roller 80, which cam and roller move the bar 81 in directions transverse to the line of carriage travel. Said cam 78 is adapted to cam the nose upward and means not shown are provided for ringing the bell when said nose drops off of the cam. The roller 80 is so located as to cam the nose 90 83 downward, thus rocking the bar 81 in the other direction from the cam 78. Near its left-hand end said bar 81 has a hook 84 depending therefrom and when the bar is rocked by the roller 80 said hook is moved 105 toward the front of the machine into the path of the hooked upper end of a link 85 which at its lower end is pivoted to the arm 55 of the rock shaft 46 and at its upper end is guided by a screw 86 passing through a 110 slot in the link 85. The construction is such that at every actuation of the universal bar 45 the link 85 moves downward, but when the bar 81 is rocked by the roller 80 the hooked upper end of the link 85 will be 115 locked by the hook 84 and the universal bar 45 will thereby be locked against operation. The bar 81 is provided with a spring 120 restoring device comprising a puppet 87, with a wide head, which bears against the flat under side of the bar. Said puppet is mounted in a barrel 88 having a compression spring in the bottom thereof.

It will be noted that this line lock thus far described and which is the line lock heretofore in use in the Smith Premier machine, locks the universal bar 45 and does not lock the space key. A second slide 75, mounted on the bar 73, carries a margin stop 89 which arrests the carriage when the latter is drawn 130

back to the right to begin a new line, said stop consisting of a lug projecting from the adjustable slide.

The carriage is capable of being moved on past where the roller 80 operates the line lock, a margin release key, presently to be described, being provided for this purpose, and said carriage is provided with a final line locking device consisting of a cam arm 110 depending from a bail 111 which, by means of arms 112, is suspended from the typewriter carriage, said bail constituting part of the carriage release mechanism of the machine. The cam arm 110 is so disposed that when the carriage approaches the extreme left-hand position to which it is capable of traveling, said cam arm rides over the bolt 82, as shown in Fig. 3, and depresses said bolt and rocks the bar 81 and throws in the lock 84.

At the extreme end of its travel the carriage is positively arrested by means of stops which include a lug 113 which projects from the underside of the carriage 7, near the end of said carriage, as shown, for example, in Figs. 2 and 3. This lug is adapted to strike the upwardly and forwardly projecting end of a screw 114 which is screwed in from the rear through the stationary rail 10 at or about the mid-length of said rail.

The escapement wheel has rigidly connected therewith a ratchet wheel 115 which is engaged by a spring pressed pawl 116 adapted to prevent backward rotation of said ratchet wheel and of the escapement wheel 22.

When under ordinary conditions the carriage is drawn back toward the right until it is arrested by its margin stop 89, the pawl 116 prevents backward turning of the escapement wheel 22 and the carriage is allowed to return by reason of the backward turning of the pinion 21. This pinion is connected to the escapement wheel by a ratchet-toothed clutch 25, which clutch can yield and allow the return motion of the carriage, or the return of the carriage can be accompanied by an operation of the carriage release mechanism, most of which is not here illustrated but the effect of which is to move the clutch member 25 toward the rear and thus let the pinion 21 run free. In either event the escapement wheel 22 is stationary during the return motion of the carriage and when the carriage is arrested by the margin stop the clutch member 25 engages the pinion 21 and causes the carriage to come to rest at a predetermined letter space position, depending upon the adjustment of the margin stop. The fault, which it is the principal purpose of my invention to correct, has arisen when, after causing the roller 80 to move beyond the bolt 83 to write additional matter beyond the ordinary line locking position, the carriage has reached a point where the line-lock has again been thrown in by the cam arm 110. If the carriage is withdrawn as soon as the line lock is thus thrown in, it will be arrested by the margin stop and will be positioned correctly. But, if, after said line lock has been thrown in, the space key were given one or two operations, the carriage would move another space or two toward the left until it was positively arrested by the stops 113, 114. In this event the last operation of the space key would not have resulted in a complete step of the carriage; and after said last operation, the carriage would not be held by the normally engaged one of the dogs 26, but said dog would stand between two of the teeth of said wheel, which wheel would thus have made some fraction of a step. When the carriage was withdrawn to the right under these conditions and arrested by the margin stop, and the clutch 25 had caught against the pinion 21, the feed dogs being between two teeth of the escapement wheel would allow the carriage to make a single step in advance of the position to which it would have been brought under normal conditions, with the result that the next line of writing would begin not at the same letter space as the other lines of writing, but one letter space to the right thereof, and the neatness of the page of writing would be marred. If, for example, the margin stop was set to cause each line to begin at "10" on the carriage scale, then every time the carriage was brought down by the space key to a full stop the next succeeding line would begin at "11" instead of "10".

In order to correct this fault I have provided special means whereby the line locking mechanism not only locks the printing keys but locks the space key also so that the additional operation of said space key, after the printing keys have been locked, cannot take place and the occasional indentation of the margin will be prevented. This locking means includes a lever 90, Fig. 3, of the first order pivoted at 91 in a bracket 92 secured by screws 93 to the top plate 2. The forward arm of said lever 90 is connected by means of the link 94 with the arm 71 of the yoke-piece 70 to which arm said link is pivoted as by a cotter-pin 95. The construction is such that whenever the space key is operated the link 94 is pulled downward and the rear arm of the lever 90 is moved upward. But said rear arm lies beneath the rearwardly directed arm of the bar 81 and in such position that when said bar 81 is in its normal position the lever 90 can rock freely, but when said bar 81 is cammed down by the roller 80 or cam 110 to locking position, as shown in Fig. 3, then said bar 81 will intercept said lever 90 and prevent the rocking of said lever and, con-

sequently, will prevent operation of the space key.

The line lock release of the Smith Premier machine includes a key, the stem of which is connected to an arm on a fore and aft rock shaft 98 journaled in the frame plates 3 and 4. The key and its stem are not shown because they would interfere with the showing of the space bar connections in Fig. 1. Near its rear end said shaft has an arm 100 to which is pivoted the lower end of a link 101 which at its upper end is pivoted to an arm 102 of a rock shaft 103 suitably journaled at the under side of the top plate 2. Said rock shaft at its inner end is bent upward, forming an arm 104 which passes through a suitable opening in the bolt 82 of the line-lock mechanism. The construction is such that when the key 96 is depressed the shaft 103 is rocked so as to move the arm 104 toward the front of the machine, thus withdrawing the nose 83 of the bolt 82 out of the way of the roller 80, whereupon the bar 81 rocks back to its normal position and releases the lock. The shaft 103 is provided with a restoring spring 105 which normally holds the bolt 82 in its rearmost position. It will be perceived that when the ordinary line-lock is released by this release key the auxiliary space key lock is also released by the return of the bar 81 to its normal position.

Various changes can be made in the details of construction and arrangement without departing from my invention.

What I claim as new and desire to secure by Letters Patent, is:—

1. In a typewriting machine, the combination of a carriage, a space key, a lever adjacent said carriage and mechanically connected to and vibrated only by said space key, and a part displaced by said carriage, said part when so displaced serving to intercept said lever and thereby to lock the space key.

2. In a typewriting machine, the combination with a carriage, an escapement, printing keys, a connection from said printing keys to said escapement, a space key, and an independent connection from said space key to said escapement, of a line locking bar, means whereby said bar when operated at the end of a line locks said printing keys, and independent means whereby said bar locks said space key.

3. In a typewriting machine, the combination with a carriage, an escapement, printing keys, a universal bar for said printing keys connected to said escapement, a space key and an independent connection from said space key to said escapement, of a line locking bar, means whereby said line locking bar when operated at the end of a line locks said universal bar, and independent

means whereby said line locking bar locks said space key.

4. In a typewriting machine, the combination with a carriage and a space key, of a part that is moved in one direction, by the carriage at the end of a line, and a second part that is moved in the opposite direction, on the depression of said space key, said parts being so related that when the first recited part is moved by the carriage it blocks the motion of the second recited part and of the space key.

5. In a typewriting machine, the combination with a carriage, a space key, printing keys, and line lock mechanism including a part that is displaced by said carriage at the end of a line and a lock for said printing keys controlled by said device; of a line lock for said space key comprising a lever separate from said printing key locking mechanism, said lever being connected with said space key and normally vibrated freely thereby, said lever being in position to be intercepted directly by said displaceable device when the latter is operated at the end of a line.

6. In a typewriting machine, the combination with a carriage, a space key, printing instrumentalities and line lock mechanism for said printing instrumentalities, said mechanism including a line lock bar located adjacent the carriage, means whereby said carriage displaces said bar at the end of a line and means controlled by said bar for locking said printing instrumentalities; of means for locking said space key including a part separate from said means for locking the printing instrumentalities, said separate part being located adjacent said displaceable bar and connected to said space key and adapted normally to be vibrated freely by said space key but in such position as to be intercepted by said bar when said bar is displaced at the end of a line.

7. In a typewriting machine, the combination with a carriage, printing keys, a universal bar for said keys, and line lock mechanism for locking said universal bar, said line lock mechanism including a device adjacent said carriage and carriage controlled means for displacing said device, of a space key, and a lever adjacent said carriage and said device, said lever being separate from said universal bar locking mechanism and being connected with said space key and normally vibrated freely thereby, but intercepted directly by said device to lock the space key when said device is displaced by the carriage.

8. In a typewriting machine, the combination with a carriage, printing keys, a universal bar for said keys, and line lock mechanism for locking said universal bar, said line lock mechanism including a bar adja-

- cent said carriage and means carried by said carriage for rocking said bar, of a space key, a lever separate from said universal bar locking mechanism and being connected 5 with said space key and normally freely vibrated thereby, said lever being so situated as to be intercepted directly by said bar to lock the space key when said bar is rocked by said carriage.
- 10 9. In a typewriting machine, the combination with a carriage, an escapement, printing keys, a universal bar for said printing keys connected with said escapement, a space key and an independent connection from 15 said space key to said escapement, of a line locking bar, means whereby said line locking bar when operated at the end of a line locks said universal bar, and a lever separate from said universal bar locking mechanism and being connected with said space key and 20 normally vibrated freely thereby, said lever being directly locked by said bar when the latter is operated.
- Signed at Syracuse, in the county of Onondaga and State of New York, this 18th 25 day of November, A. D. 1916.
